(57) **CLAIM**

The ornamental design for a gaming machine, as shown.

DESCRIPTION

A gaming machine embodying the ornamental design disclosed herein is intended to be mounted on a pedestal and used by a player to participate in wagering or other games.

FIG. 1 is a left perspective view of gaming machine embodying the ornamental design according to the present invention.

FIG. 2 is a right perspective view of the gaming machine shown in FIG. 1.

FIG. 3 is a left side view of the gaming machine shown in FIG. 1.

FIG. 4 is a right side view of the gaming machine shown in FIG. 1.

FIG. 5 is a front view of the gaming machine shown in FIG. 1.

FIG. 6 is a rear view of the gaming machine shown in FIG. 1.

FIG. 7 is a top view of the gaming machine shown in FIG. 1; and,

FIG. 8 is a bottom view of the gaming machine shown in FIG. 1.
